J. H. HOWARD.
BURGLAR PROOF SAFE.
APPLICATION FILED AUG. 24, 1910.

1,029,996.

Patented June 18, 1912.

UNITED STATES PATENT OFFICE.

JAMES H. HOWARD, OF MEDFORD, MASSACHUSETTS.

BURGLAR-PROOF SAFE.

1,029,996.

Specification of Letters Patent. Patented June 18, 1912.

Application filed August 24, 1910. Serial No. 578,647.

To all whom it may concern:

Be it known that I, JAMES H. HOWARD, of Medford, in the county of Middlesex and State of Massachusetts, have invented certain new and useful Improvements in Burglar-Proof Safes, of which the following is a specification.

This invention relates to an improvement in safes designed to provide extraordinary security against unlawful access to the contents of the safe, and more particularly is an improvement on and extension of the invention covered in my prior Patent No. 819,430, dated May 1, 1906.

15 Briefly stated the invention consists in providing in the interior of the safe a box or cage of material designed to resist both the impact of hammer blows and the action of cutting tools, and one or more sides of 20 which are vented to permit free escape of gases generated by any explosive which may be put into the safe.

In the accompanying drawings I have illustrated several forms in which my invention may be practically embodied, and the mode of its use, although without attempting to show all possible modifications or constructions which may be made within the scope and spirit of the invention, or all 30 the modes in which it may be used. Merely a sufficient showing is made to illustrate the principles of the invention and to illustrate the fact that these principles may be embodied in many forms.

35 In the drawings Figure 1 represents a horizontal sectional view of a safe having my invention applied thereto. Fig. 2 is a perspective view of the vented inner box or cage removed from the same. Fig. 3 is a 40 perspective view of the safe with the cage in place. Figs. 4, 5, 6 and 7 are views showing modified forms of construction of the whole or parts of the cage. Figs. 8, 45 9 and 10 are detail sectional views of elements or bars from which the cage may be constructed, illustrating the mode of making the same resistant both to the action of cutting tools and the impact of hammer blows.

50 The same reference characters indicate the same parts in all the figures.

The improvement forming the subject matter of the present invention consists of a box or cage *a* adapted to be set inside of a safe, 55 which is otherwise of ordinary construction,

and to be immovably secured therein by being wholly or partially embedded in the cement filling of the safe walls, where cement is used, or of being secured by bolts, lugs or the like, suitably secured to the cage and embedded in the cement filling. In Fig. 1 the cement filling of the safe walls is represented at *b*, and is surrounded by the usual metal plates *d* forming the outer walls, and the angle irons *e* which bind the corners of the same. A door at the front of the safe is represented by *c*.

The cage is vented in one or more of its walls, such walls or sides being made as a grille work or perforated plates or the like, having openings or vents of such size as to permit the gases generated by explosion of a charge of powder or dynamite to pass freely through them without injurious effect, while being at the same time small enough to prevent removal of the valuables from the safe after the outer walls thereof may have been blown open by the explosion.

My object is not to construct a safe incapable of being blown open, for such result is not practically possible with portable safes adapted for office use, but to provide a protected safe having an inner lining which remains intact after the outer walls 85 may have been opened by explosives, owing to the fact that the vents in the lining permit free escape of the gases generated by explosion and so prevent rupture thereof. The lining however is so firmly attached to 90 the walls of the safe that, although an opening may be effected through the outer walls, it will be impossible in the limited time at the command of the burglar, after producing an explosion, to remove and carry off 95 the cage bodily. The cage is, also, constructed of members composed in part of material so ductile as to be uninjured by impact of hammer blows, and in part of material too hard to be cut by saws, chisels or 100 the like, and which, although consequently brittle, is so intimately and continuously united to the ductile material, that it cannot be broken away therefrom. Thus I propose to make the vented walls of the cage 105 out of bars composed of alternate strips *f* and *g* of high carbon steel and low carbon steel or iron welded together, as shown in Fig. 8, or of a tubular envelop of ductile material *f* inclosing a core *g'* of high car- 110

bon steel, as shown in Figs. 9 and 10, the latter figure showing merely a prismatic form of bar rather than a circular form, as shown in the other figures. The vented 5 walls of the cage may be made of such bars welded or otherwise securely attached together to form a network, or one or more walls of the cage may be made of laminated plates having a composite structure 10 similar to that illustrated in Fig. 8 of alternate layers of hard and soft steel.

I propose to use a cage constructed as thus defined, either in connection with the vented inner door illustrated and described 15 in my prior patent referred to, or without such inner door. In the latter case the cage will have one open side directed toward the doorway of the safe, and the safe as a whole will then be purposely so constructed that 20 it is weaker at some other point than at the connection between the doors and the sides, top and bottom. A safe so protected may designedly be made weak in its outer portion so that a charge of powder will readily burst 25 open the outer walls and make its escape through the vents of the guard, without injuring the latter. The guard, although then exposed, is able to defy the attacks of the burglar by reason of its composite structure 30 which resists both hammer blows and cutting tools, and is so securely anchored to the heavy parts of the safe that it cannot be bodily carried away.

The cage as shown in Figs. 1, 2 and 3, is 35 designed to be wholly or partially embedded in the cement filling of the safe walls, and the sides thereof are made into a unitary structure:

Fig. 6 shows a construction in which each 40 wall of the cage may be independent of the others, consisting of a frame *h*, to which rods for forming a grille may be attached by welding or otherwise, or it may be a continuous plate having perforations. These 45 frames or plates are each provided with lugs *i* projecting outwardly so that they may be embedded deeply and firmly in the cement filling of the safe and the several plates or frames to form the complete cage are assembled 50 within the corresponding walls of the safe to make a continuous cage.

In Fig. 4 is shown a frame made as a casting with which several of the sides may be 55 integrally cast, and to which their vented sides may be secured by welding or otherwise. Walls such as shown in Fig. 7 may be provided in a cage having a frame as 60 shown in Fig. 4. Certain of these walls may be continuous plates such as the plate *j*, and one or more of the walls may be perforated plates as the plate *k*.

In Fig. 5 is shown a framework for an 65 inner cage made of rods *l* bent to form the bounding edges of the cage, and having eyes at their end portions embracing other rods

at the corners. The rods forming the grilles sides of the cage, or the perforated plates, are adapted to be assembled within these binding rods, or otherwise suitably secured thereto.

For the purpose of assembling walls such as shown in Fig. 6 together for forming a cage, or for attaching such walls to a frame, I provide the walls with lugs *i'*, in which are apertures *i*² for the reception of rivets 70 or other fastenings, which also pass through the overlapping edges of adjacent walls or the members of a frame. Similarly the plates *j* and *k* shown in Fig. 7 have apertures *j'* and *k'* to receive rivets passing 75 through holes *j*² and *k*² in the bars of the frame shown in Fig. 4. The rivets may be of material similar to that from which the bars of the cage are made, or other material, and when the cage is in place in the safe, 80 these fastenings are so embedded in the filling of the safe that they are inaccessible to a safe-breaker, and so cannot be removed.

I claim,—

1. In combination with a safe having continuous fire-proof walls, a vented lining contained within the top, bottom, back and sides of the safe.

2. In combination with a safe having continuous fire-proof walls, a burglar proof 95 vented inner cage forming five sides of a parallelepiped and set into the interior of the safe.

3. A safe having a door adapted to be secured in closed position and being constructed so that the fastening between the door and walls of the safe is stronger than the weakest portion of the safe, and a burglar-resisting inner cage set within the safe and 100 having an open side toward the door, said cage being constructed with vents, so as to permit escape through its vents of gases generated by explosives, whereby the weakest point of the safe will fail and the cage with the door may form a complete burglar 105 proof container for valuables.

4. In a safe an outer shell of material refractory to heat a cage set within the interior thereof, and lining the top, bottom, back and sides, said cage having one or more 115 of its walls vented to permit free escape of the gases of an explosive charge, and being constructed of material resistant to shock and cutting tools.

5. A safe having walls and a door of fire 120 proof material including a filling of cement or similar material, and a lining for said safe comprising a box or cage-like structure of material resistant to shock and cutting tools, embedded to a greater or less extent in the cement, and being vented to permit escape of the gases of explosive compounds.

6. The combination with a safe having impervious inclosing outer walls, an inner 125 burglar-proof cage forming a lining for the 130

safe and having sides, back, top and bottom of openwork construction and permanently united to one another as by welding, the parts of said cage having vents whereby the 5 gases generated by combustion of explosive compounds may escape without harming the cage, although destroying the outer walls, and the members of which the cage is composed being formed of both hard and ductile

metal placed in intimate contact, whereby to resist breaking and cutting.

In testimony whereof I have affixed my signature, in presence of two witnesses.

JAMES H. HOWARD.
